UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed November 3, 1925. Serial No. 66,493.

This invention relates to compressor unloaders, but more particularly to a regulator for unloading and loading a compressor step by step.

5 The invention is in some respects an improvement upon the device disclosed in U. S. Patent No. 1,430,578, granted to me October 3, 1922, for a compressor regulator, in which the clearance valves are held closed by receiver pressure and assisted in opening by springs when the receiver pressure is released.

10 In the present invention substantially the reverse of this is true, since I have devised means for opening the clearance valves by the application of receiver pressure, and depend upon other means, such as springs, for closing the valves.

15 The usual type of clearance regulator is not conveniently applicable for the purposes of the present invention, and my object is primarily to secure a simple and efficient regulator by means of which the valves which unload the compressor may be positively opened and held open by receiver pressure. The regulator has a wide application and is not confined to clearance control, but may be used in cases in which the unloading steps are effected by other than clearance 20 chambers and valves, as will be readily apparent to those skilled in the art, and the unloader may be applied to single or multi-stage compressors.

25 To these and other ends, which will hereinafter appear, the invention consists of the regulator hereinafter fully described and claimed in this specification and shown in the accompanying drawings, in which—

30 Figure 1 is a diagrammatic view partly in longitudinal section and partly broken away, of a two-stage compressor having the regulator applied thereto;

35 Figure 2 is an enlarged detail side elevation of the regulator partly in vertical section;

40 Figure 3 is a transverse sectional plan view taken through the central portion of the regulator valve chest on the line 3—3 of Figure 4;

45 Figure 4 is a diagrammatic vertical sectional view through the regulator valve chest on the line 4—4 of Figure 3 looking in the

direction of the arrows, and assuming that the ports and passages have all been brought into one plane to better illustrate the distribution of the actuating fluid, and

50 Figure 5 is a detail vertical sectional elevation through the valve chest on the line 5—5 of Figure 3 looking in the direction of the arrows.

55 The regulator is applicable to various types of compressors, whether single or multi-stage, but in the present instance I have chosen, for illustrative purposes, to show the regulator applied to a two-stage 60 compound compressor having a low pressure cylinder A and double acting piston B, and a high pressure cylinder C and double acting piston D. The pistons having the piston rods E and F may be driven from any 65 suitable source or sources of power (not shown), and the cylinders are provided with the usual clearance spaces G and H communicating with the cylinders and controlled by suitable normally closed clearance valves 70 T, having the valve casings 1, 2, 3 and 4 mounted on the air heads O and P of the cylinder B. The compressor valves Q for the cylinder A and the compressor valves R for the cylinder B, which may be of the 75 plate type for instance, are mounted in the air heads and serve as inlet or discharge valves in the usual manner. The compressor cylinders are assumed to be connected by suitable piping to each other and to the 80 main receiver tank S, the piping not being shown for the sake of simplicity.

85 Each clearance valve T is provided with a stem U having a head V between which and the outer end of the valve casing a compression spring W is preferably located, tending to close the valve, while the opposite side of the valve head is intermittently subjected to pressure fluid from the receiver S for opening the valve. The supply of 90 pressure fluid to the inner faces of the valve heads V successively is controlled by a regulator X forming the subject matter of this invention, actuated by a pressure fluid device, which may be in the form of a diaphragm controlled lever Y movable in accordance with successively attained receiver 95 pressures.

100 The valve casings 1, 2, 3 and 4 of the

cylinder A are connected respectively to the similarly numbered valve casings, 1, 2, 3 and 4, of the cylinder B by means of the pipes 1^a, 2^a, 3^a and 4^a, which are in turn connected by branch pipes 1^b, 2^b, 3^b and 4^b to the valve chest Z of the regulator X, so that the clearance valves T are operated in pairs. The valve chest Z is provided with a plurality of main valve chambers a conveniently arranged around a common center, and fluid actuated main regulator valves b having the heads c and the stems d, are longitudinally movable in the valve chambers for controlling the distribution of fluid to and from the valve casings 1, 2, 3 and 4, and the movements of the valves T for step-by-step loading and unloading of the compressor. An auxiliary valve chamber e is located centrally in the valve chest Z between the main valve chambers a, and an auxiliary valve f, connected to be actuated by the fluid pressure lever Y, is longitudinally movable in the auxiliary valve chamber e for controlling the distribution of fluid to the main valve chambers and the movements of the main regulator valves b.

The main valve chambers a and auxiliary valve chamber e preferably extend through the chest Z from end to end, and the main valve chambers are located in pairs with the chambers of each pair sufficiently close together so that a common inlet passage g extending transversely in the valve chest substantially centrally, intersects all of the main valve chambers a at the ports g' and also the auxiliary valve chamber e, as indicated diagrammatically in Figure 3 and shown also in Figure 5. This forms a simple construction and reduces the number of parts and passages in the valve chest. The main inlet passage g is suitably connected to the pipe h leading to the receiver, by means of the branch pipe j.

The valve chest Z is provided with an end plate k, in this instance a bottom plate, suitably secured thereto by means of the tap bolts o, and a cover p is secured over the top of the valve chest by means of the tap bolts q. The end or bottom plate k is provided with an exhaust opening r communicating with the central auxiliary valve chamber e and adapted by suitable ports and passages in the valve chest Z and end plate k, controlled by the central auxiliary valve f, to be placed in communication successively with one end of each of the main valve chambers a and with the branch pipes 1^b, 2^b, 3^b and 4^b, leading to pairs of clearance valves T, for releasing the receiver pressure at the forward faces of the pistons V of said pairs of valves to permit the valves to close successively under the influence of the valve springs W. The cover p is provided with an exhaust passage s, adapted to be placed in communica-

cation by suitable ports and passages in the valve chest and cover, successively with the other ends of the main valve chambers a. Exhaust pipes t and u leading from the exhaust opening r and the exhaust passage s respectively, may be connected to a common exhaust pipe v open to atmosphere.

Referring more particularly to the construction of the regulator, the valve chest Z may be formed of any suitable material, 75 as for instance bronze, which does not rust and avoids sticking of the valves. A bushing w, also preferably of bronze, forms a lining for the central auxiliary valve chamber e, in which bushing the auxiliary valve 80 f, having the heads x and y, is actuated by means of the valve stem z passing through the stuffing box 5 and pivotally connected to the pressure fluid lever Y at the point 6 by means of the yoke 7. The bushing w 85 is provided with central ports 8 and 9 and two series of ports 1^c, 2^c, 3^c and 4^c and 1^d, 2^d, 3^d and 4^d, which series of ports are controlled by the auxiliary valve heads y and x respectively, for admitting pressure to 90 and exhausting pressure from the end pressure surfaces of the auxiliary valves b, the arrangement of ports and passages in the regulator being such that when pressure is supplied to one end pressure surface of an auxiliary valve b for moving the valve in one direction, the opposite end pressure surface of the valve is opened to the atmosphere, and vice versa.

The branch pipes 1^b, 2^b, 3^b and 4^b as shown, communicate respectively with the chambers 10 in the valve chest Z, separated from the chambers 11 by the bridges 12, and the chambers 10 and 11 communicate with the main valve chambers a by means of the ports 13 and 14 respectively. Slides 15, carried by the main regulator valves b, control the ports 13 and 14 and these slides may be in the form of shoes held between the shoulders 16 on the valve stems d 110 and prevented from rotating by means of the transverse pins 17. The main valves b may be guided and prevented from rotating by means of the dowels 18.

Gaskets 19, of any suitable material as 115 rubber or fiber, are preferably placed between the valve chest Z and the end plate k and cover p, and properly perforated to conform to the ports and passages in the parts of the regulator. The material of the 120 gaskets preferably over-laps the main regulator valve chambers a at the points 20 in order to form a cushion and a seal for the main regulator valves against which overlapping portions of the gaskets the valve heads impinge on their operation. Removable plugs 21 closing the apertures 22 in the cover p, in axial alignment with the main regulator valves, afford accessibility to the 125 interior of the regulator and permit oiling. 130

The fluid pressure lever Y which actuates the central auxiliary valve f may be of any suitable form or construction, but in this instance is in the form of an arm pivoted at 23 to the frame or support 24, carrying adjustable weights 25 at its outer end. The lever rests on the upper end of a pin 26 supported in the guide 27, carried by the diaphragm 28 which is subjected to receiver pressure from the receiver S through the pipe h. A given increase of pressure in the receiver will expand the diaphragm 28 and carry the lever Y upwardly, thus moving the auxiliary regulator or valve f upwardly a given distance. A coiled spring 29, supported between the regulator frame 30 and the cap 31 pinned to the rod 32, which is pivoted to the lever Y at the point 33, resists the upward movement of the lever Y. A stop 34 on the rod 32 limits the downward movement of the lever.

In the operation of the apparatus let it be assumed that the compressor has been operating with all the clearance valves T closed, and held in closed position by the springs behind the heads V of the valves. The lever Y would then be at the limit of its downward movement and all the main regulator valves b would be in their upward position, as Figure 4 is viewed, that is they would all be in the position of the main regulator valve b at the right of said figure, and the auxiliary regulator valve f would be at the limit of its downward travel.

In such case, the respective valve casings of the clearance valves T on both cylinders are open to atmosphere through the pipes 1^b, 2^b, 3^b and 4^b and the remaining pipes connected thereto, since the pairs of chambers 10 and 11 in the regulator casing are placed in communication by the slides 15, and the chambers 11 are open to atmosphere through ports 50, common passage 51 in the end plate h and atmospheric pipes t and v. The clearance valves are thus all held closed by their springs.

The main regulator valves b would all be held in upward position, as Figure 4 is viewed, due to receiver pressure from the main inlet passage g through the respective series of ports 1^c, 2^c, 3^c, and 4^c, thence through the chambers 34, ports 35 and 36, and passages 37, and to the end pressure surfaces of the main regulator valve heads c, tending to hold the valves upward. The opposite end pressure surfaces of the main regulator valves on the opposite heads c are opened to exhaust through the passages 38, ports 39 and 40, chambers 41 and the series of ports 1^d, 2^d, 3^d and 4^d and thence around the auxiliary regulator valve f directly to the exhaust passage s.

Let it then be assumed that there is a sufficient increase of receiver pressure be-

neath the diaphragm 28 of the lever Y to raise the lever and the auxiliary valve f the first step to the position of the auxiliary valve f indicated in Figure 4, so that the auxiliary valve heads y and x have uncovered the ports 1^c and 1^d. The lower end pressure surface of one main regulator valve b controlling the branch pipe 1^b leading to the clearance valves T in the valve casings 1 will be exhausted to atmosphere through the exhaust pipe t. Receiver pressure is also admitted to the opposite end pressure surface of the said main regulator valve b from the main inlet pipe g through the port 1^d, chamber 41, ports 40 and 39, and passage 38, to the main valve chamber a for said valve. The valve will be thrown to its opposite position and the slide 15 places the ports 13 in communication with the pressure fluid pipe g, which supplies the receiver pressure to the heads V of the clearance valves T in the valve casings 1, through the pipes 1^a and 1^b and thus opening the said clearance valves to unload the compressor the desired degree.

At successively attained receiver pressures, the pairs of clearance valves are successively opened as the auxiliary regulator valve f continues to uncover pairs of ports in the two series of ports 1^c, 2^c, 3^c and 4^c and 1^d, 2^d, 3^d and 4^d. The pairs of clearance valves are successively closed automatically as the auxiliary regulator valve f is moved in the opposite direction.

I am not to be understood as limiting the invention to the details of construction shown and described since those skilled in the art may devise equivalent constructions for carrying out my invention, as defined in the appended claims.

The regulator disclosed is structurally designed so that the receiver pressure may be efficiently applied for positively opening the clearance valves. Each main valve b has a definite function to perform and controls the supply of receiver pressure to actuate the clearance valves in an opening direction. This construction is also advantageous in case some or all of the unloading steps are effected by holding open one or more of the inlet valves as in the so-called "free air" unloading system.

I claim:

1. In a compressor unloader, the combination of a compressor cylinder and piston, a receiver, a clearance chamber for the cylinder, a normally closed clearance valve having a cylinder and piston, a regulator having a valve chest, a controlling valve in said valve chest automatically responsive to receiver pressure, a fluid connection between said valve chest and the forward face of the piston in the cylinder of said clearance valve, and ports and passages in said regulator for controlling the supply and release

of receiver pressure in said fluid connection to the clearance valve piston, whereby the clearance valve is positively and automatically opened by receiver pressure and closed by release of said pressure.

2. In a compressor unloader, the combination of a compressor cylinder and piston, a receiver, a clearance chamber for the cylinder, a normally closed clearance valve having a cylinder and piston, a regulator having a valve chest, an auxiliary controlling valve in said valve chest, automatically responsive to receiver pressure, a main regulator valve in said regulator, a fluid connection between said main regulator valve and the forward face of the piston in the cylinder of the clearance valve, and ports and passages in said regulator for controlling the main regulator valve and thereby controlling the supply and release of receiver pressure in said connection to the clearance valve piston, whereby the clearance valve is positively and automatically opened by receiver pressure and closed by release of said pressure.

ceiver pressure and closed by release of said pressure. 25

3. In a compressor unloader, the combination of a cylinder and piston, a receiver, a clearance chamber for the cylinder, a normally closed clearance valve having a cylinder and piston, a regulator having a controlling valve automatically responsive to receiver pressure, a pressure fluid connection between said regulator and the forward face of the piston in the cylinder of the clearance valve, and ports and passages in said regulator for controlling the supply and release of receiver pressure in said pressure fluid connection to the clearance valve piston, whereby the clearance valve is positively and automatically opened by receiver 30 pressure and closed by release of said pressure. 35

In testimony whereof I have signed this specification.

CHESTER W. METZGAR CHESTER W. METZGAR.
